(57) **CLAIM**

The ornamental design for the curtain rod bracket, as shown and described.

DESCRIPTION

FIG. 1 is a perspective angled front view of the curtain rod bracket, which embodies my design;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a bottom view thereof; and,

FIG. 8 is another perspective view thereof.

The dash-dash broken lines in the drawings illustrate portions of the curtain rod bracket that form no part of the claimed design; the additional, dash-dash broken lines in FIG. 8 are for purposes of illustrating environmental subject matter only and forms no part thereof. The dash-dot-dash broken lines in the drawings define the bounds of the claimed design and form no part thereof.
